US00D570487S

(12) **United States Design Patent** (10) Patent No.: **US D570,487 S**
Richenberger (45) Date of Patent: ** Jun. 3, 2008

(54) **ROBOTIC POSITIONING DEVICE FOR A PATIENT TABLE**

(75) Inventor: **Michael Richenberger**, Erlangen (DE)

(73) Assignee: **Siemens Aktiengesellschaft**, Munich (DE)

(**) Term: **14 Years**

(21) Appl. No.: **29/291,365**

(22) Filed: **Aug. 24, 2007**

(30) **Foreign Application Priority Data**

Mar. 1, 2007 (EM) 000690011

(51) **LOC (8) Cl.** 24-02

(52) **U.S. Cl.** D24/184

(58) **Field of Classification Search** D24/183-184, D24/231-232, 234; D15/199; 74/490.01-490.05; 219/124.35, 639; 221/210; 318/560; 378/65, 378/197, 209; 600/407, 424; 601/5; 606/1, 606/424

(57) **CLAIM**

The ornamental design for robotic positioning device for a patient table, as shown and described.

DESCRIPTION

FIG. 1 is a front view of the robotic positioning device for a patient table;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a perspective view thereof.

1 Claim, 7 Drawing Sheets

FIG. 1

FIG. 2

FIG. 3

FIG. 4

FIG. 5

FIG. 6

FIG. 7
